UNITED STATES PATENT OFFICE.

GEORGE M. FISCHER, OF AUSTIN, ILLINOIS, ASSIGNOR TO JERSEY-CREME COMPANY, OF FORT WORTH, TEXAS, A CORPORATION OF TEXAS.

DESIGN FOR A JAR.

No. 39,959.

Specification for Design.

Patented May 4, 1909.

Application filed February 8, 1909. Serial No. 476,861. Term of patent 3½ years.

To all whom it may concern:

Be it known that I, GEORGE M. FISCHER, a citizen of the United States, residing at Austin, in the county of Cook and State of Illinois, have invented a new, original, and ornamental Design for a Jar, of which the following is a specification, reference being had to the accompanying drawing, forming part thereof.

The figure is an elevation of a jar showing my new design.

I claim:

The ornamental design for a jar as shown.

GEORGE M. FISCHER.

Witnesses:

Wm. H. BELT,
M. O. KIDDIE.
